Alexander S. Strouse.

UNITED STATES PATENT OFFICE.

ALEXANDER S. STROUSE, OF POTTSVILLE, PENNSYLVANIA.

SHIRT.

SPECIFICATION forming part of Letters Patent No. 358,822, dated March 1, 1887.

Application filed April 14, 1886. Serial No. 198,872. (No model.)

To all whom it may concern:

Be it known that I, ALEXANDER S. STROUSE, of Pottsville, in the county of Schuylkill and State of Pennsylvania, have invented a new and useful Improvement in Shirts; and I do hereby declare that the following is a full, clear, and exact description of the same.

My invention relates to shirts of that class known as "dress" or "outside" shirts, and has for its object, first, to render it convenient to replace the neckband or wristbands, when worn or partially worn out, before the rest of the shirt is in a similarly worn-out condition, and at the same time to retain the original shape and form of the parts from which they are detached and prevent the loosening and fraying out of the gathered portions of the garment. In general, to so simplify the detaching and attaching of the neckband or wristbands, so as to enable any person, whether skilled or unskilled in the art of making and constructing shirts, to do the same and practically renew a shirt when worn or partially worn out at these parts.

My invention consists in certain details of construction, hereinafter fully set forth, and specifically claimed.

In the drawings hereunto attached, and forming part of this specification, Figure 1 represents my improved shirt with neckband and wristbands detached. Fig. 2 represents the same with the neckband and wristbands in place. Fig. 3 represents a section through the wristband and a portion of the sleeve on line

35 *x x* of Fig. 1.

As is well known, the neckband or wristbands of a shirt are usually worn out before any other portion of the garment. Under the old method of constructing shirts at the neck and sleeve, the worn or partially worn out bands could not be detached without the risk of having the neck or sleeve ends lose the gathers and fray out, thus losing their original shape and fit. Another difficulty attending the detaching of neckband or wristbands of a worn or partially worn out shirt is in the danger of destroying the material of the garment to which the same are to be attached, and which danger is entirely avoided and overcome by

50 my invention.

In carrying out my invention I make the

shirt at the neck in the usual and ordinary way; but in addition thereto, and before attaching the neckband, I stitch a binding of muslin or linen around the edge of the neck, 55 as shown at A by Fig. 1 of the drawings, and before attaching the wristbands I also stitch a binding of linen or muslin around the end of sleeves in like manner, as shown at C by Fig. 1 of the drawings. After the binding of 60 linen or muslin has been sewed around the edges of the neck and sleeves the ordinary neckband and wristbands are attached thereto by sewing, in the usual way. By interposing the binding *a* and *c* between the neck and 65 sleeves of the garment and the neckband and wristbands it will be understood that they may be readily detached and replaced by new ones without in any way interfering with the set of the shirt at the points indicated, as the 70 binding will always keep the shape, and when the bands are detached or attached they are simply-detached from or attached to the binding.

I purpose putting up with each shirt duplicate neckbands and wristbands of the same size and shape as those attached to the shirt, so that when the originals are worn or partially worn out the duplicates may be attached to the garment. I also purpose manufacturing 75 neckbands and wristbands of all sizes and shapes, on each of which bands will be marked the true and correct measurement of the same. This will enable persons to secure a perfect-fitting neckband or wristbands to replace such 80 as may be worn or partially worn out.

What I claim is—

A shirt having the neck-opening or wrist-opening provided with a binding over the edge of the said opening, and having secured 85 supplemental thereto the ordinary neckband or wristbands, whereby the said bands may be renewed without altering the fit of the shirt, as set forth.

In testimony whereof I have hereunto set 90 my hand and name to this specification in the presence of two witnesses.

ALEX. S. STROUSE.
